WASHING MACHINE SUPPORTING
CARRIAGE

Alfred R. Oberwegner, Los Angeles, Calif.

Application March 31, 1947, Serial No. 738,465

3 Claims. (Cl. 29—288)

1

My invention relates generally to supporting devices, and particularly to a supporter, holder, or jig adapted to support various objects, such as washing machines and similar appliances and equipment, to facilitate assembly and repair of their parts. Specifically, the invention pertains to a mobile supporting device in which a washing machine, or the like, may be held, and which is so constructed that it can be adjusted to different angular positions to locate the operating mechanism of the machine within convenient reach of the workman assembling, repairing, or servicing the machine.

When assembling, repairing, and servicing electrical appliances, such as domestic clothes washing machines, wherein the electric motor, driving mechanism, and water pump are located beneath the tub or clothes receptacle of the machine, it is customary to turn the machine on its side or bottom side up in order to make it possible to work upon the operating parts. Due to the fact that no means has heretofore been provided for lifting and supporting the washing machines in such positions, it has been necessary to manually lift and turn the machines and rest them on their sides or bottom sides up on the floor, or upon a suitable work-bench or table. Since such machines are relatively heavy and awkward to handle, the placing thereof in convenient positions is quite a laborious operation and requires considerable time and energy.

It is an object of my invention to obviate the difficulties encountered, when servicing and repairing domestic washing machines and similar equipment, by providing a holder or supporting device onto which the machine may be readily wheeled and clamped, and which may be adjusted to different angular positions to dispose the operating mechanism of the machine in convenient locations to facilitate working thereon.

Another object is to provide a supporting device, of the character referred to, having a base or chassis and a frame or saddle onto which the washing machine may be wheeled and clamped, the frame being pivotally connected to the base to adapt it to be tilted to different angular positions for the purpose explained above.

Another object is to provide a device of the type indicated in which the base is provided with caster-wheels to adapt the machine to be moved to different locations, and it is a further object to provide readily operable means for locking the tiltable frame in its different positions of angular adjustment.

Another object is to provide a device of the ⁵⁵ 20, to be next described.

2

character specified having a particularly simple, yet highly efficient, clamping means for retaining the washing machine on the pivoted frame, such means being quickly operated and incorporating fastening devices engageable with either the rim of the washing machine receptacle or the rim of its frame, so that washing machines in fully assembled or partly assembled condition may be supported.

10 Another object is to provide a supporting device which is relatively simple in construction, being composed of a minimum number of parts adapted for economical manufacture and assembly, and one which is strong and durable in use.

15 Further objects of the invention are set forth in the following specification, which describes a preferred embodiment thereof, by way of example, as illustrated by the accompanying drawings. In the drawings:

20 Fig. 1 is a perspective view of my supporting device;

Fig. 2 is a perspective view of the device, as viewed in the opposite direction from Fig. 1, illustrating the manner of supporting a complete 25 domestic washing machine in substantially inverted position to facilitate working on its lowermost operating parts;

Fig. 3 is a view similar to Fig. 2, showing a partly disassembled washing machine mounted in the device, and illustrating the device as adjusted to a position to retain the machine on its side;

Fig. 4 is a vertical sectional view through the clamping means, taken on line 4—4 of Fig. 1; and,

25 Fig. 5 is a cross-sectional view, taken on line 5—5 of Fig. 2, and showing the locking means.

Referring to the drawings in detail, my supporting device comprises a base 10, which includes a pair of side members 11 and 12 which are arranged in parallel relation throughout substantially one-half their length, the remaining portions diverging outwardly. The side members 11 and 12 are connected by means of tie-bolts 13, and each has a caster-wheel 14 at each of its ends to adapt the device to be moved along a surface, such as a floor, in any direction. Welded, or otherwise secured, to the side members 11 and 12, midway between their ends and projecting upwardly therefrom, are uprights or standards 15 and 16, preferably constructed from channel-iron sections. At their upper ends, the standards 15 and 16 carry transverse pivot pins 17 and 18 for pivotally supporting a frame 45

The frame 20 consists of a pair of substantially vertical side members 21 and 22, constructed from channel sections, which are joined at their upper ends by an angle-iron strip 23. The lower ends of the side members 21 and 22 are connected by a pan-shaped element 25 into which the lower castered ends of the legs of a domestic washing machine may be placed, in the manner to be explained hereinafter. Attached to the forward side of the connecting element 25 is a pair of transversely spaced elements 26, which are similar but of shorter length than the element 25. The side member 21 has an apertured ear 28 for receiving the pivot pin 17, while the side member 22 has a disc-like ear 29 for receiving the pivot pin 18. It is thus seen that the frame 20 is pivotally mounted on the standards 15 and 16, so that it can be tilted from the substantially vertical position, shown in Fig. 1, to the inverted position, illustrated in Fig. 2, or to an intermediate position, as indicated in Fig. 3.

Secured to the side members 21 and 22, adjacent their upper and lower ends, are curved metal bands 31 and 32, respectively, each band carrying a resilient pad 33 at its ends. The bands and their pads form, in effect, curved rests against which the periphery of the tub of the washing machine is adapted to engage.

The washing machine is adapted to be clamped on the frame 20 in a vertical direction by clamping means next described. Welded to the rearward side of each band 31 and 32 are bearing blocks 35 and 36 (Fig. 4) in which a screw-shaft 37 and a guide-rod 38 are rotatable. The upper ends of the screw-shaft 37 and rod 38 project upwardly above the top of the frame 20 and through a block 39, the rod being secured in place therein by a pin 40 while the screw-shaft 37 is rotatable therein and carries a hand-wheel 41 at its upper projecting end. It is thus seen that by rotating the hand-wheel 41 and shaft 37 the latter is screwed upwardly or downwardly in the bearing block 36, depending upon the direction of such rotation, to raise and lower the block 39. Referring to Figs. 1 and 4, a bar 44 is slidable in a transverse hole in the block 39 and has a keyway 45 in which the inner end of a set-screw 46 is adapted to engage, to retain the bar in different positions of adjustment in the block. The bar 44 has a head 47 at its forward end, and fastened to the forward face of the head is a hook-like clamping element 48 having a resilient lining 49. The element 48 is adapted to engage over the rim of the tub of the washing machine, and, by screwing the block 39 downwardly, the element acts to force the entire washing machine downwardly to clamp it on the frame 20. Attached to the bottom of the head 47 by a screw 50 is a resilient tube 51 adapted to engage against the side of the washing machine tub. It is sometimes desirable to support a washing machine from which the tub has been removed (Fig. 3), and in this case a clamping element 55, shown in Figs. 1 and 3, is utilized. The element 55 consists merely in a plate mounted on the rod 38 and adjustably secured thereon by a set-screw 56. The element normally is swung to the inoperative position, shown in Fig. 1, but may be pivoted forwardly into position to overlie the rim of the base of the washing machine when necessary. The clamping element 55 may have a resilient pad 57 on its lower surface.

The frame 20 is adapted to be tilted to any of the positions shown in Figs. 1, 2, and 3, and locking means are provided for retaining the

frame in any of these positions. The locking means comprises a locking element or latch 60, which is arranged to slide vertically against the inner surface of the standard 16, as shown in Fig. 5, and has a bent upper end 61 which projects through an aperture 62 in the standard, and which is adapted to enter any one of three notches 63, 64, and 65, provided in the curved edge of the pivot ear 29 of the frame 20. The latch 60 is urged upwardly into locking engagement by a spring 66, but is adapted to be withdrawn from the locking position by the depression of a pedal 67 formed at its lower end.

The supporting device is operated in the following manner: Assuming that it is necessary to service or repair a conventional type of domestic washing machine, such as that shown at 70 in the present drawings, with the frame 20 of the device in the position shown in Fig. 1, the washing machine is tilted slightly and the ends of its legs 71 are placed in the element 25, or the elements 26, depending upon the size and type of washer to be supported. To clamp the washer 70 on the frame 20, it is merely necessary to turn the hand-wheel 41 in a direction to screw the shaft 37 downwardly to cause the hook 49 to engage over the rim of the tub 72 of the washer, as shown in Fig. 4. In this manner, the washing machine is securely clamped on the tiltable frame 20. The side of the tub 72 rests against the pads 33 of the upper band 31, it being noted that washers having depending sides would also contact the pads of the lower band 32.

To turn the washing machine 70 bottom side up, the frame 20 is swung on its pivot pins 17 and 18 to the position illustrated in Fig. 2. During this pivotal movement, the pedal 67 is depressed to withhold the latch 61 from the notches of the disc 29. Upon the frame 20 approaching the inverted position, shown in Fig. 2, the pedal 67 is released to permit the latch 61 to be projected into the notch 65 whereby to retain the frame in this position. The washing machine 70 thus is positioned with its bottom side up, so that the workman can repair, replace, or service the operating parts, indicated at 73, and located beneath the tub 72. After working on the operating mechanism, the latch 61 is moved to inoperative position and the frame 20 returned to first position, the clamping hook 48 released, and the washing machine readily removed by lifting its legs 71 out of the holder 25. It will be noted that because the base 10 is mounted on castor-wheels 14, the supporting device may be moved to any location along a floor when empty or when supporting a washer.

When a washing machine, from which the tub has been removed, is to be supported in the device, its castor-wheels are placed in the holder 25, after which the ends of a belt 75 carried by the sides of the frame 20 are brought around and fastened together, as shown in Fig. 3, to hold the washer in place. The washer is then clamped down by swinging the clamping element 55 into position to cause it to overlie the rim of the base 76 of the washer, and the hand-wheel 41 is turned to depress the clamping element. When it is desirable to tilt the washer to the inclined position, shown in Fig. 3, the latch 61 is permitted to enter the notch 64 to maintain the frame in this position of adjustment. If the washer is to be supported with its axis arranged horizontally, the latch 61 may be inserted in the notch 63. While the supporting device is herein shown as supporting a washing machine of con-

ventional type, it will be apparent that it may be used to hold washers of other models. The device may be used, in plants where washers, and like appliances, are manufactured, as an assembly jig.

While I have herein shown and described the supporting device, as embodied in a preferred form of construction and applied to use in a specific manner, it is to be understood that various changes might be made in the structure thereof, and in the manner of applying it to use, without departing from the spirit or scope of the invention. Therefore, without limiting myself in this respect, I claim:

1. A device for supporting a domestic washing machine, or the like, in different positions, comprising: a base member; a frame pivoted on a horizontal axis on said base member to adapt it to be tilted to different positions of angular adjustment, said frame having a cradle against which the side of the machine is disposed, longitudinally spaced bearings on said frame, one of said bearings being internally screw-threaded; a shaft rotatable in said bearings and having screw threads engageable with the internal threads of said one bearing; a block carried by said shaft and in which said shaft is rotatable; a hand-wheel fast on said shaft; a rod secured to said block and slideable in said bearings to prevent rotation of said block; and a clamping member carried by said block and adapted to engage the rim of the tub of the machine, when the block is moved in one direction; and interengaging locking means on said base member and said frame for releasably locking said frame in its different angular positions.

2. A device for supporting a domestic washing machine, or the like, in different positions, comprising: a base member; a frame pivoted on a horizontal axis on said base member to adapt it to be tilted to different positions of angular adjustment, said frame having a cradle against which the side of the machine is disposed; longitudinally spaced bearings on said frame, one

of said bearings being internally screw-threaded; a shaft rotatable in said bearings and having screw threads engageable with the internal threads of said one bearing; a block carried by said shaft and in which said shaft is rotatable; a hand-wheel fast on said shaft; a rod secured to said block and slideable in said bearings to prevent rotation of said block; and a clamping hook carried by said block and adapted to engage the rim of the tub of the machine, when the block is moved in one direction; a clamping element adjustably secured to said rod and adapted to engage the base of the machine to retain the machine in place on said frame; and interengaging locking means on said base member and said frame for releasably locking said frame in its different angular positions.

3. A device as defined in claim 2 in which said cradle, said clamping hook, and said clamping element are provided with resilient pads engageable with the washing machine, and including a resilient tube associated with said hook and engageable with the side of the tub below its flared rim.

25 ALFRED R. OBERWEGNER.
